US0D1060247S

(12) **United States Design Patent** (10) Patent No.: **US D1,060,247 S**
(45) Date of Patent: ** Feb. 4, 2025

(54) **ELECTRICAL GENERATOR**

- (71) Applicant: **Cummins Generator Technologies Limited**, Peterborough (GB)
- (72) Inventors: **Daniel Ciochina**, Peterborough (GB); **Mihai Cristian Ilinca**, Peterborough (GB); **Silviu Ionut Nanau**, Peterborough (GB); **Viorel Visan**, Peterborough (GB); **Paul Camil Stirbu**, Peterborough (GB); **Stefan Laurentiu Simion**, Peterborough (GB)
- (73) Assignee: **Cummins Generator Technologies Limited**, Peterborough (GB)
- (**) Term: **15 Years**
- (21) Appl. No.: **29/826,546**
- (22) Filed: **Feb. 14, 2022**

Related U.S. Application Data

- (62) Division of application No. 29/703,843, filed on Aug. 29, 2019, now Pat. No. Des. 947,125.

(57) **CLAIM**

The ornamental design for an electrical generator as shown and described.

DESCRIPTION

FIG. 1 is a top, front, left isometric view of an electrical machine according to the claimed design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and,
FIG. 7 is a bottom plan view thereof.

Any broken lines in the figures illustrate portions of the electrical generator that form no part of the claimed design.

1 Claim, 7 Drawing Sheets
